UNITED STATES PATENT OFFICE.

WILLIAM J. NEWTON, OF BRIDGEPORT, CONNECTICUT, ASSIGNOR TO HARVEY HUBBELL, INCORPORATED, OF BRIDGEPORT, CONNECTICUT, A CORPORATION OF CONNECTICUT.

ELECTRIC SWITCH, (FLUSH, SURFACE, PUSH-BUTTON.)

1,346,553.

Specification of Letters Patent. Patented July 13, 1920.

Application filed November 18, 1918. Serial No. 262,958.

To all whom it may concern:

Be it known that I, WILLIAM J. NEWTON, a citizen of the United States, residing at Bridgeport, county of Fairfield, State of Connecticut, have invented an Improvement in Electric Switches, (Flush, Surface, Push-Button,) of which the following is a specification.

This invention has for its object to provide electric switch mechanism operating on the toggle principle, which shall do away with the relatively slow sliding movement of the movable contacts over the fixed contacts, in mechanisms of this character, and effect a practically instantaneous make and break, the vital feature of the invention being that the movable contacts are carried by a swinging contact member and remain in either the open circuit or closed circuit position until a blow is delivered upon the contact member by an actuating member, itself controlled by a powerful spring acting upon a toggle joint, the contact member remaining in either position without any movement whatever until the blow is delivered and then moving instantly to the reverse position.

In the accompanying drawings forming a part of this specification I have illustrated the application of the invention to flush, surface and push button switches.

Figure 1 is a plan view of a surface switch, the face plate being indicated by dotted lines;

Fig. 2 a longitudinal section on the line 2-2 in Fig. 1 looking in the direction of the arrows;

Fig. 3 a longitudinal section on the line 3-3 in Fig. 1, looking in the direction of the arrows;

Fig. 4 a longitudinal section on the line 4-4 in Fig. 1, looking in the direction of the arrows;

Fig. 5 a transverse section on the line 5-5 in Fig. 4, looking in the direction of the arrows;

Fig. 6 a plan view of a surface switch complete;

Fig. 7 a similar view with the cap removed;

Fig. 8 a section on the line 8-8 in Fig. 7, looking in the direction of the arrows;

Fig. 9 a section on the line 9-9 in Fig. 7, looking in the direction of the arrows;

Fig. 10 a plan view of a push button switch, the face plate being removed; 55

Fig. 11 a longitudinal section on the line 11-11 in Fig. 10, looking in the direction of the arrows, and

Fig. 12 is a perspective view of the swinging contact member detached. 60

As the types of switches illustrated differ only in details of construction, I shall use, so far as practicable, the same reference numerals in describing the several forms of the invention which I have illustrated. 65

The important elements of the invention are the operating member 20, the toggle arm 21, the actuating member 22, the spring 23, the contact member 24, contacts 25 carried by said member, a frame 26 by which said parts are carried, and fixed contacts 27.

Turning now to Figs. 1 to 5, inclusive, 28 denotes the upper insulating block of a flush switch, 29 the lower insulating block, 30 the top plate, and 31 screws by which said parts are secured together. Within the insulating blocks is a recess 32 which receives the frame and the parts carried thereby, the frame being secured to the lower insulating block by screws 33. The fixed contacts are formed 70 upon contact carriers 34 which are provided with binding screws 35 and are secured to the lower insulating block by screws 36.

The operating member 20 is pivoted to the frame, in the present instance, in a hub 85 37 forming part of the frame and is a lever of the first order. The toggle joint consists of the inner arm of the operating lever and the toggle arm, indicated by 21. The toggle arm is provided with a head 38 having a notch to receive a cross pin 39 in a slot in the inner end of the operating member. The actuating member comprises a strip of metal bent to U-shape, the branches of which are pivoted to the frame as at 40. 95 The inner end of the toggle arm passes through a hole in the cross piece of the actuating member. 41 denotes an angle piece, shown as resting upon the inner face of the cross piece, which may or may not be used 100 as preferred. The spring 23, in the present instance, is a relatively strong compres-

sion spring, surrounds the toggle arm and bears against the head of said arm and against the cross piece, or against the angle piece if used, washers 42 being interposed 5 between the ends of the spring and the head of the toggle arm and the angle piece or cross piece.

The general shape of the contact member will be clearly understood from Fig. 12. It 10 comprises broadly side pieces 43 which are pivoted to the frame as at 44 and spaced apart cross pieces 45 which bridge the side pieces. The actuating member lies between the side pieces of the frame, and the side 15 pieces of the contact member are pivoted on the outer side of the side pieces of the frame. The cross pieces of the contact member are spaced apart far enough to give full effect to the blows of the actuating member as will be more fully explained. In the 20 present instance I have shown two pairs of fixed contacts 27, and two pairs of contacts 25 carried by the contact member. Contacts 25 are formed at the ends of metallic strips 25 46 which are effectually insulated.

The operation is briefly as follows: In Figs. 1 to 5, inclusive, the parts are shown in the open circuit position. As the operating member is swung toward the center from 30 the position shown, the spring will be compressed and will move the toggle to its neutral position. The actuating member will move away from the cross piece of the contact member with which it has been in 35 engagement, but no movement can be imparted to the contact member until the toggle has passed its neutral position. As soon as the toggle has passed this position the entire expansive power of the spring will be 40 exerted to cause the actuating member to move forward instantly and strike a relatively powerful blow upon the other cross piece of the contact member, the effect of which is to throw the contact member instantaneously to the other extreme of its movement and either open or close the circuit, in 45 the present instance, a closing of the circuit is produced. It is important to note that no movement of the contact member can be produced except by a blow of the actuating member, thus the danger of arcing is practically eliminated. It should be noted furthermore that the movements of the contact member receive a positive stop through the 50 engagement of the cross pieces with the side pieces of the frame.

Turning now to Figs. 6 to 9, inclusive, which illustrate the application of the invention to a surface switch, 47 denotes an 60 insulating base to which the frame is secured by screws 48. The fixed contacts, indicated by 27 as before, are formed upon plates 49 which are secured to the base by screws 50. The construction and operation of the essen-

tial parts of the invention are precisely the 65 same as before.

Turning now to Figs. 10 and 11, which illustrate the application of the invention to a push button switch, the construction is the same as in the first form with the exception 70 of the change in the operating member necessary to adapt it for operation by push buttons instead of by swinging it manually. The operating member in this form is provided at its upper end with a cross arm 51. 75 52 denotes the push buttons, each of which is provided with a lug 53 which is pivoted to an end of the cross arm.

Having thus described my invention, I 80 claim:

1. In a switch, the combination of a swinging contact member, a swinging actuating member, an operating member, a toggle arm one end of which is pivoted to the operating member, the other end having operative connection with the actuating member, the operating member and the toggle arm comprising a toggle joint, co-operative engaging parts on the contact and actuating members spaced in inoperative positions, 90 and means acting to cause the actuating member to be accelerated to strike the contact member when the toggle joint is swung past its dead center in either direction, the contact member remaining in either the 95 open circuit or closed circuit position until it receives the blow of the actuating member.

2. In a switch, the combination of a swinging contact member, an actuating member, an operating member, a toggle arm one end of which is pivoted to the operating member, the other end having sliding engagement with the actuating member, the operating member and the toggle arm comprising a toggle joint, co-operative engaging parts on the contact and actuating members spaced in inoperative positions, and a spring acting to cause the actuating member to be accelerated to strike the contact member when the toggle joint is swung past its 100 dead center, the contact member remaining in either the circuit opening or circuit closing position until it receives a blow from the actuating member.

3. In a switch, the combination of a 115 swinging contact member, an actuating member, an operating member, a toggle arm having a head pivotally connected to the operating member, the other end of the toggle arm having operative engagement with 120 the actuating member, the operating member and the toggle arm comprising a toggle joint, co-operative engaging parts on the contact and actuating members spaced in inoperative positions, and a spring bearing 125 against the head of the operating arm and against the actuating member and acting to cause the actuating member to be accelerated

- to strike the contact member and throw it to the opposite extreme of its movement when the toggle joint is swung past its dead center.
5. 4. In a switch, the combination of a frame, a contact member, a U-shaped actuating member pivoted thereto, an operating member independently pivoted to the frame, a toggle arm pivoted to the operating member and having a head, the other end of said toggle arm passing through the cross-piece of the actuating member, and a compression spring bearing against the head of the toggle arm and against the cross-piece of the actuating member, said operating member and toggle arm comprising a toggle joint, coöperative engaging parts on the contact and actuating members spaced in inoperative positions, and the spring acting to throw the actuating member to the extreme of its movement causing it to strike the contact member and throw the latter to the extreme of its movement when the toggle joint is swung past its dead center.
10. 5. In a switch, the combination of a swinging contact member, a swinging U-shaped actuating member, an operating member, a toggle arm pivoted to the operating member and passing through the cross-piece of the contact member, said operating member and toggle arm comprising a toggle joint, coöperative engaging parts on the contact and actuating members spaced in inoperative positions, and a spring compressed by the toggle action and acting against the actuating member to throw said member to the extreme of its movement causing the actuating member to be accelerated to strike the contact member and throw the latter to the extreme of its movement when the toggle joint is swung past its dead center.
15. 6. In a switch, the combination of a swinging U-shaped actuating member, an operating member, a contact member, coöperative engaging parts on the contact and actuating members spaced in inoperative positions, a toggle arm pivoted to the operating member and passing through the cross-piece of the actuating member, said operating member and toggle arm comprising a toggle joint, an angle piece carried by said cross-piece and a spring compressed by the toggle action and adapted to bear against either angle of the angle piece to cause the actuating member to be accelerated to strike the contact member when the toggle joint is swung past its dead center, the blow of the actuating member throwing the contact member to the opposite extreme of its movement.
20. 7. In a switch, the combination of a contact member, coöperative engaging parts on the contact and actuating members spaced in inoperative positions, an actuating member, 65 an operating member, and a spring controlled toggle connection between the operating member and the actuating member, whereby the actuating member is caused to be accelerated to strike the contact member 70 and throw it to the opposite extreme of its movement when the toggle connection is swung past its dead center.
25. 8. In a switch, the combination of a contact member, an actuating member, an operating member, a toggle arm pivotally connected to the operating member and having a sliding connection with the actuating member, said operating member and toggle arm comprising a toggle joint, coöperative engaging parts on the contact and actuating members spaced in inoperative positions, and a spring acting to throw the toggle joint to the extreme of its movement when the joint is swung past its dead center, whereby 85 the actuating member is caused to be accelerated to strike the contact member and throw it to the other extreme of its movement.
30. 9. In a switch, the combination of a contact member, an actuating member, an operating member, coöperative engaging parts on the contact and actuating members spaced in inoperative positions, a toggle arm having a sliding connection with the actuating member and having a head pivotally connected to the operating member, said operating member and toggle arm comprising a toggle joint, and a spring bearing on said head and on the actuating member whereby the latter 100 is caused to be accelerated to strike the contact member and throw it to the other extreme of its movement when the toggle joint is swung past its dead center.
35. 10. In a switch, the combination of a contact member, a U-shaped actuating member, an angle piece on the cross-piece of the actuating member, an operating member, coöperative engaging parts on the contact and actuating members spaced in inoperative 105 positions, a toggle arm having a sliding connection with the actuating member and having a head pivotally connected to the operating member, said operating member and toggle arm comprising a toggle joint, and a spring bearing against the head and against the angle piece whereby the actuating member is caused to be accelerated to strike the contact member and throw it to the other extreme of its movement when the toggle joint is swung past its dead center.
40. 11. In a switch, the combination of a contact member, a U-shaped actuating member, an angle piece carried by the actuating member, an operating member, a toggle arm having a sliding connection with the actuating member and having a head pivotally connected to the operating member, a compression 115

- 4
- sion spring carried by the toggle arm, and washers between the ends of the spring and said head and said angle piece, respectively.
12. In a switch, a frame, a contact member comprising side pieces pivoted to the frame and spaced apart cross pieces, an actuating member independently pivoted to the frame and lying between the cross pieces normally in spaced relation therewith, an operating member, a toggle arm pivoted to the operating member and having sliding connection with the actuating member, and a compression spring carried by the toggle arm, and bearing against the actuating member.
13. In a switch, a U-shaped frame, a contact member comprising side pieces pivoted outside the side pieces of the frame and spaced apart cross pieces, a U-shaped actuating member pivoted inside the side pieces of the frame and lying between the cross pieces of the contact member, an operating member, a toggle arm pivoted to the operating member and having sliding connection with the actuating member, and a compression spring carried by the toggle arm, whereby the actuating member is caused to strike a cross piece of the contact member and throw said member to the opposite extreme of its movement, the movement of the contact member being stopped by engagement of the cross piece with the frame.
14. In a switch, the combination of a swinging contact member, a swinging actuating member, coöoperative engaging parts on the contact and actuating members spaced in inoperative positions, and spring controlled toggle mechanism which normally retains the actuating member at an extreme of its movement and causes the actuating member to strike a blow upon the contact member and carry said member to be accelerated to the opposite extreme of its movement when the toggle mechanism is swung past its dead center.
15. In a switch, the combination of a swinging contact member, a swinging actuating member, and spring controlled toggle mechanism acting on the actuating member to normally retain both members at an extreme of their movement, said mechanism causing the actuating member to strike a blow upon the contact member when the toggle mechanism is swung past its neutral position.
